UNITED STATES PATENT OFFICE.

HENRY O. D. SEGRAVE, OF LONDON, ENGLAND.

DESIGN FOR AN AUTOMOBILE BODY.

Application filed April 30, 1927. Serial No. 21,809. Term of patent 3½ years.

To all whom it may concern:

Be it known that I, HENRY O. D. SEGRAVE, a subject of the King of Great Britain, residing at 12 Princes Street, in the town of London, England, have invented a certain new, original, and ornamental Design for an Automobile Body, of which the following is a specification, reference being had to the accompanying drawing, forming part hereof.

In the drawing—

I claim:—

The ornamental design for an automobile body, substantially as shown.

In testimony whereof, I affix my signature.

HENRY O. D. SEGRAVE.
